WALL CONSTRUCTION

Frank La Grotta, New York, N. Y., assignor to
Conver Steel & Wire Co., Incorporated, a cor-
poration of New York

Application January 13, 1940, Serial No. 313,734

5 Claims. (Cl. 72—46)

This invention relates to a wall construction and is particularly directed to a frame which may be constructed entirely of metal, may be pre-fabricated, may be shipped in a knocked down condition, may be easily assembled and may be so installed and assembled that it will accommodate the normal service mains regardless of their positions and yet will positively maintain the necessary rigidity.

In the drawings:

Figure 1 is a perspective view, partly broken away, of such a wall frame wherein are disclosed a base, channel studs and a top runner;

Figure 2 is a vertical sectional view on line 2—2 of Figure 1, partly broken away and enlarged;

Figure 3 is a horizontal sectional view on line 3—3 of Figure 2;

Figure 4 is a perspective view of a furring and spacer clip;

Figure 5 is a fragmentary perspective view partly broken away of a modified form of the base;

Figure 6 is a section on lines 6—6 of Figure 5; and

Figure 7 is a section on lines 7—7 of Figure 6.

In the form of the invention illustrated in Figures 1 to 4 inclusive, a base is provided which includes runners that are in the form of strips 1. These strips are formed, preferably, of metal. The strips are in spaced relation to each other and are held in this spaced relation by clips 2 that are suitably secured to the strips 1 as by welding, for instance. These clips 2 are arranged in spaced relation longitudinally of the base, providing spaces therebetween for a purpose that will later be described. The upper edges of the strips 1 are not secured permanently together but are secured in definite spaced relation by spacer clips.

Each of these clips includes a body portion 3, the end portions 4 of which extend at angles to the body portion. Tongues 5 extend from the body portion 3 at an outward angle thereto. These spacer clips are formed preferably of metal and the tongues 5 are resilient for a purpose that later will be described.

At the upper edges of the runners flanges 6 are formed. These flanges extend inwardly toward each other and at an angle to the runners. The flanges 6 in addition to extending inwardly extend downwardly and have spaced apertures 7 therein that extend longitudinally of the flanges and are adapted to receive the tongues 5 of the spacer clips.

Openings 8 that are adapted to receive the wall studs are provided in the spacer clips and each is arranged preferably closer to one end of the clip than the other.

In constructing this base of metal the runners may of course be rolled and the clips 2 secured thereto by welding while the spacer clips may be produced by stamping. Thus the simplest operations are employed in the production of the base, reducing the cost of production to the minimum.

The base with the spacer clip removed therefrom may be shipped to the construction where it is to be used. The base may be secured to the foundation, such as a floor, beam or the like by nailing or similarly securing the same thereto through the holes in the clips 2.

The spacer clips may then be attached to the runners 1 by inserting the tongues 5 through the apertures 7 in the flanges 6. When thus inserted the angular ends 4 of the spacer clips will engage the faces of the flanges 6 and the shoulders at the ends of the clips will engage the flanges to prevent the runners from moving toward each other. The tongues 5 will resiliently engage the runners at the points of contact between the runners and the ends of the tongues. This engagement will hold the spacer clips firmly in position and will prevent the runners from moving away from each other.

The wall studs are inserted in the openings 8 in the spacer clips and are thus positioned at their lower ends. The upper ends of the wall studs are positioned by insertion in openings 10 in a top runner that is adapted to be secured to or adjacent the ceiling. This top runner includes a horizontal web 11 in which the openings 10 are provided, a horizontal web 12 for attachment to the ceiling or the like and an intermediate web 13 joining the other two webs together. The purpose of offsetting the opening 8 in the spacer clip is so that when the lathing is secured to the wall studs it will be as nearly as possible in the middle of the ultimate wall.

With this construction the spacer clips may be shifted as required to accommodate service mains, such as pipes, wires, etc., that pass upwardly through the ultimate wall, and of course if necessary certain of the clips 2 may be removed without disturbing the unity of the construction.

In the above description I have referred to the use of the invention in a partition wall but the invention is also applicable to a furring. In the latter case one of the runners 1 may be omitted and the remainder of the base with its associated

parts used, in which event the ends of the clips 2 and the free tongues 5 of the spacer clips will engage and bear against the base wall such for instance as the outer wall of a building.

In the form of the invention shown in Figures 5 to 7 inclusive the runners 1' have flanges 6' bent inwardly toward each other at both the upper and lower edges of the runners to form channels therebetween.

In this form a spacer and fastener clip 14 is provided which clip has ears 15 thereon for engagement beneath the flanges 6'. At the lower end of each clip 14 a portion 16 is bent at an angle and is provided with a hole for a securing element such as a nail or screw. Thus the runners 1' will be secured together and to the floor by the spacer and fastener clips 14 and as these clips may be shifted longitudinally of the base at will and to any desired extent during installation they may be accommodated to the service mains hereinbefore referred to.

Clips 3 of a construction similar to that of the spacer clips hereinbefore described in connection with Figures 1 to 4 are provided in the form of the invention illustrated in Figures 5 to 7, and are assembled with the runners in a similar manner. When thus assembled they will accommodate the wall studs and because of their resilient engagement with the runners will maintain the whole assembly in tight relationship.

Thus I have provided a frame for a wall construction that may be made entirely of metal by the simplest manufacturing operations, one which may be shipped in a knocked down condition and one which may easily be assembled, one which may be so adjusted in assembling that the service mains may be accommodated regardless of their position and one in which the wall studs may be located at the will of the installer.

While I have described particular embodiments of my invention, it must be realized that modifications in the details thereof may be made without departing from the appended claims.

I claim:

1. In a metallic baseboard construction, a pair of spaced runners having inwardly turned aper-

tured flanges at their upper edges, spacer and fastener clips having tongues extending into the said apertures and resiliently engaging the inner walls of the runners to maintain the clips in position and to normally urge the runners apart.

2. In a metallic baseboard construction, spaced runners having inwardly and downwardly turned apertured flanges at their upper edges, spacer and fastener clips including body portions and upwardly turned end portions engaging the downwardly turned flanges, and resilient tongues extending through said apertures and resiliently engaging the inner walls of the runners.

3. In a baseboard construction, spaced runners having inwardly-turned apertured flanges at their upper edges, means for securing the lower edges together, and spacer and fastener clips including body portions bridging the space between said flanges and resilient tongues engaging in said apertures and resiliently engaging the inner walls of said runners, the distance between the ends of said tongues being normally greater than the distance between the inner faces of said runners.

4. In a metallic baseboard construction, a pair of spaced runners having inwardly turned apertured flanges at their upper edges, spacer and fastener clips having tongues extending into the said apertures and resiliently engaging the inner walls of the runners to maintain the clips in position and to normally urge the runners apart, and means for securing the lower edges of the runners in spaced relation.

5. In a metallic baseboard construction, spaced runners having inwardly and downwardly turned apertured flanges at their upper edges and inwardly and upwardly turned flanges at their lower edges, spacer and fastener clips having tongues extending through said apertures in the upper flanges and resiliently engaging the inner faces of the runners, spacer clips extending between the runners and having ears engaging the said inwardly turned flanges, and means for securing the lower edges of the runners to the floor of a building construction.

FRANK LA GROTTA.
